EDMUND UHER, JR., OF BUDAPEST, HUNGARY, ASSIGNOR TO UHERTYPE A. G., OF GLARUS, SWITZERLAND, A FIRM OF SWITZERLAND

CONTROLLING DEVICE

Application filed February 4, 1927, Serial No. 185,997, and in Germany January 4, 1927.

The invention relates to a controlling device of the kind in which travelling selectors are employed and which are adapted for use in many ways such for example as for the 5 generation of definite signs of light or sound, for the operation of light sensitive compositor machines and of electrical or mechanical switching apparatus and the like and it consists in an arrangement and construction 10 of the controlling mechanism whereby the selectors acting as contact members or abutments are capable of being varied practically indefinitely on a support on which they are carried similarly to the printing signs in type 15 setting, and are controlled and corrected in their position temporarily and adapted in any desired combination to be used either in continuity or after one or repeated use to be readily removed from the support on which 20 they are arrayed when in use.

The accompanying drawings illustrate by way of example two constructional forms of the invention:

Fig. 1 represents a novel controlling device 25 in a vertical transverse section.

Fig. 2 is a similar partial section of the selector drum showing the ball passages used in this instance but not the keyboard.

Fig. 3 is a top plan view of Fig. 1 showing 30 in an exposed manner only a portion of the selector drum and of the ball passages, a central portion of the drum hood and some of the ball passages and part of the keyboard.

Fig. 4 shows in detail some contact points 35 of the drum viewed from below and

Fig. 5 is a plan view or plotted diagram illustrating a distribution of the selectors.

Mounted on an insulating bar 1 is a series 40 of individual contact springs or tongues 2 each of which is connected to an individual conductor 3. In the instance shown the device is intended for the operation of a light sensitive compositor machine for which purpose there are as many contact members 2 45 and individual conductors 3 as there are printing signs to be photographed with the aid of the various circuits. It is obvious, however, that the device could readily be used also for controlling a piano or Jacquard 50 loom or the like in which cases the number

of the contacts would be dependent respectively on the number of strings or warp threads etc.

Rotatable about an axis 4 in the direction of the arrow shown is a drum 5 the mantle of which is provided in the plane of each tongue 2 circumferentially with a girdle of cavities 6. The row of tongues 2 extends into the path of balls 7 herein referred to as selectors which therefore come into contact with these 60 tongues 2. The drum 5 is connected in any suitable way to one pole of an electric source, the other pole of which is branched off to the tongues 2. As soon, therefore, as a ball 7 comes into contact with the requisite tongue 65 2 it causes the corresponding circuit to be closed, so that the balls 7 or other equivalent bodies that may be used constitute in fact selectors which are adapted to control the various circuits provided for the performance 70 of various functions.

The balls 7 or the like are according to this invention placed on the drum 5 in a free condition and are temporarily retained in their positions in one or the other manner as hereinafter stated by reference to Fig. 1.

Arranged below and opposite each girdle 80 of cavities or selectors is an inclined channel 8 filled with balls 7, so that the latter tend successively to roll towards a charging point 9. Each channel 8 is associated with a spindle 10 by terminating in the end of a guide 11 for the same. The width of said guide is equal to the size of a ball 7 necessitating therefore only the manipulation of one spindle 10 for the 85 raising of one ball 7 into its position on the drum 5.

In order to effect this operation the drum 5 is rotated intermittently and the spindles 10 are actuated during the standstill of the drum, as shown by means of a keyboard comprising the keys 12 and the lever gear 13, 14 and 15. A forward extension 16 engages a fork 17 on the respective spindle 10. The key 12 individual to said spindle 10 causes the lever gear 13, 16 to assume first of all the ready position shown in Fig. 1 in which the link 15 is stiffened out by the action of a pawl 18. The actual lifting of the spindle 10 is thereafter effected with the aid of an electro- 95 100

magnet 19 which in the manner indicated in the drawing is rendered operative by the next following depression of the key thereby causing the arm 20 of a bell crank lever to be attracted, in which action the other arm 21 of said lever forces the extension 16, the fork 17 and spindle 10 together with a ball 7 thereon towards the circumference of the drum. The springs 22, 23 and 24 shown in Fig. 1 are provided to restore all parts to the initial position.

If it should be noticed that a wrong key 12 was depressed the error can be readily corrected by means of the release key 25 before the ball 7 had in fact been raised and in this manipulation the selector drum 5 need not be stopped if previously thereto it was properly set by the action of the keys 12.

The drum 5 may be a magnet so as to hold the balls 7 by attraction. In this case it could remain uncovered and the selectors once fitted on the drum could be used repeatedly or a scraper 26 (Fig. 2) could be so positioned in the track of the balls as to lift the balls 7 from the drum after they have passed the tongues 2. Where the balls 7, however, are employed quite freely the drum 5 as shown in Fig. 1 is covered by a hood 27 extending from the charging point 9 in the direction of the arrow to the tongues 2, so as to hold the balls 7 in their cavities between the charging point and the contact members referred to. This portion between 9 and 2 contains a number of consecutive selector divisions whereby by the scope of the selector adjustment is extended offering in addition an opportunity for control and correction before the balls 7 come into contact with the tongues 2. To this end the hood 27 is slotted along its upper generatrix where the free balls 7 can temporarily be exposed. The gap 28 thus formed is associated with a graduation 29 which coupled with a circular division of the drum 5 enables the position of each ball 7 to be precisely determined. Any balls that may have been inserted inadvertently in a wrong cavity may thus be picked out and their positions corrected. To this end the keys 12 cause also a record strip to be printed on in ordinary type so as to enable this control to be readily exercised. The operation of the controlling mechanism described will from the foregoing be well understood. The keys 12 are actuated like the keyboard of a typewriting machine, by which action the balls 7 are individually located on the drum 5 in succession while the latter is intermittently advanced from division to division. The proper function of the selectors sets in after their travel from the distance between 9 and 2. Fig. 5 illustrates the co-ordinated plan of one example of selector adjustment in which the balls are represented by black dots and for the sake of clearness have been shown connected one to the other by oblique lines.

Each channel 8 is associated with a rising continuation 30 by way of which each ball after passing the tongues 2 and dropping is conveyed by gravity back to the charging point 9 enabling the setting of the selector bodies to be repeated.

What I claim is:—

1. A circuit-controlling device, comprising in combination, a series of fixed contact members individually connected with one pole of a source of electrical energy, a movable carrier in electrical connection with the other pole of said source and adapted to travel past said contact members in close proximity thereto, a plurality of free contact bodies each adapted to occupy temporarily a position on said carrier thereby to form contact with one of said fixed members when moved past the same, means on said carrier to hold said bodies in selected circumferential positions on said carrier, means for selectively placing said free bodies on said carrier, in selected circumferential positions and means for returning said free bodies into position to be selected.

2. A circuit-controlling device, comprising in combination, a series of fixed contact members individually connected with one pole of a source of electrical energy, a movable carrier in electrical connection with the other pole of said source and adapted to travel past said contact members in close proximity thereto, a plurality of free contact bodies each adapted to occupy temporarily a position on said carrier thereby to form contact with one of said fixed members when moved past the same, means for selectively placing said free bodies on said carrier, permanent means on said carrier for retaining said free bodies in their selected circumferential positions until they contact with said fixed members, and means automatically operative after such contact for returning said free bodies into position to be selected.

3. A circuit-controlling device, comprising a combination, a series of fixed contact members individually connected with one pole of a source of electrical energy, a movable carrier in electrical connection with the other pole of said source and adapted to travel past said contact members in close proximity thereto, a plurality of free contact bodies each adapted to occupy temporarily a position on said carrier thereby to form contact with one of said fixed members when moved past the same, means for selectively placing said free bodies on said carrier, magnetically operative means for retaining said free bodies, means for retaining said free bodies in their selected positions until they contact with said fixed members, and means automatically operative after such contact for returning said free bodies into position to be selected.

4. A circuit-controlling device, comprising

- in combination, a series of fixed contact members individually connected with one pole of a source of electrical energy, a movable carrier in electrical connection with the other pole of said source and adapted to travel past said contact members in close proximity thereto, said carrier being provided on its surface with a plurality of circumferentially spaced cavities, a plurality of freely rolling bodies each adapted to occupy temporarily one of said cavities in said carrier thereby to form contact with one of said fixed members when moved past the same, means for selectively placing said bodies in said cavities, and automatically operative means for returning said bodies into position to be selected. 5
5. A circuit-controlling device, comprising in combination, a series of fixed contact members individually connected with one pole of a source of electrical energy, a rotatable drum in electrical connection with the other pole of said source and adapted to rotate past said contact members with its perimeter in close proximity thereto, a plurality of free contact bodies each adapted to occupy temporarily a position on said drum thereby to form contact with one of said fixed members when moved past the same, means on said drum to hold said bodies in selected circumferential positions on said drum, means for selectively placing said free bodies on said drum, and means for returning said bodies into position to be selected. 10
- 20 6. A circuit-controlling device, comprising in combination, a series of fixed contact members individually connected with one pole of a source of electrical energy, a rotatable drum in electrical connection with the other pole of said source and adapted to rotate past said contact members with its perimeter in close proximity thereto, said drum being adapted to be driven intermittently, a plurality of free contact bodies each adapted to occupy temporarily a position on said drum thereby to form contact with one of said fixed members when moved past the same, means on said drum to hold said bodies in selected circumferential positions on said drum, means for selectively placing said free bodies on said drum, and means for returning said bodies into position to be selected. 15
- 25 7. A circuit-controlling device, comprising in combination, a series of fixed contact members individually connected with one pole of a source of electrical energy, a movable carrier in electrical connection with the other pole of said source and adapted to travel past said contact members in close proximity thereto, a plurality of free contact bodies each adapted to occupy temporarily a position on said carrier thereby to form contact with one of said fixed members when moved past the same, means for selectively placing said free bodies on said carrier, permanent means on said carrier to hold said bodies in selected circumferential positions around the carrier, and a manually operable keyboard for bringing said selecting means into operation. 30
- 30 8. A circuit-controlling device, comprising in combination, a series of fixed contact members individually connected with one pole of a source of electrical energy, a rotatable drum in electrical connection with the other pole of said source and adapted to travel past said contact members with its perimeter in close proximity thereto, said drum being provided with a plurality of circumferential lines of positions, a plurality of free contact bodies each adapted to occupy temporarily one of said positions thereby to form contact with one of said fixed members when moved past the same, a movable plunger in association with each of said lines of positions for selectively placing said free members therein, means for actuating said plunger, and manually operable means for individually bringing said plunger-actuating means into action. 35
- 35 9. A circuit-controlling device, comprising in combination, a series of fixed contact members individually connected with one pole of a source of electrical energy, a rotatable drum in electrical connection with the other pole of said source and adapted to travel past said contact members with its perimeter in close proximity thereto, said drum being provided with a plurality of circumferential lines of positions, a plurality of free contact bodies each adapted to occupy temporarily one of said positions thereby to form contact with one of said fixed members when moved past the same, a movable plunger in association with each of said lines of positions for selectively placing said free members therein, means for actuating said plunger, an electromagnet adapted to operate said plunger-actuating means, and manually operable means for closing a circuit through said electromagnet. 40
- 40 10. A circuit-controlling device, comprising in combination, a series of fixed contact members individually connected with one pole of a source of electrical energy, a rotatable drum in electrical connection with the other pole of said source and adapted to travel past said contact members with its perimeter in close proximity thereto, said drum being provided with a plurality of circumferential lines of positions, a plurality of free contact bodies each adapted to occupy temporarily one of said positions thereby to form contact with one of said fixed members when moved past the same, a movable plunger in association with each of said lines of positions for selectively placing said free members therein, lever mechanism for actuating said plungers, an electromagnet adapted to operate said lever mechanism, the lever mechanism being normally out of the range of 45
- 45 50 55 60 65 70 75 80 85 90 95 100 105 110 115 120 125 130

said electromagnet, and manually operable means for shifting said lever mechanism into position to be actuated and for subsequently closing a circuit through said electromagnet.

- 5 11. A circuit-controlling device, comprising in combination, a series of fixed contact members individually connected with one pole of a source of electrical energy, a movable carrier in electrical connection with the other pole of said source and adapted to travel past said contact members in close proximity thereto, a plurality of free contact bodies each adapted to occupy temporarily a position on said carrier thereby to form
- 10 contact with one of said fixed members when moved past the same, means for selectively placing said free members on said carrier, a hood for retaining said free members in their selected positions until they contact with
- 15 said fixed members, said hood being slotted longitudinally and provided with indicia for indicating the correct positions of said free members, and means operative after contact with the fixed members for returning said free members into position to be selected.
